UNITED STATES PATENT OFFICE

GEORGE J. OVERMYER, OF HARTFORD CITY, INDIANA

FURNITURE GLIDE

Application filed May 29, 1928, Serial No. 281,418. Renewed December 1, 1930.

This invention relates to a glide or sliding shoe for use in connection with articles of furniture, one of the objects being to provide a device of this character adapted to be substituted for the ordinary detachable casters, the glide being so constructed as to permit the article of furniture to be tilted while in contact with a supporting surface without danger of cracking or breaking the glide.

10 Another object is to provide a glide which will adjust itself automatically to the contour of the surface upon which the article of furniture is resting so that under all conditions the pressures will be distributed evenly over the bottom surface of the glide.

Another object is to improve upon the construction of the glide so that the parts thereof can be assembled readily, thereby adapting the device to quantity production.

20 Another object is to provide a glide the parts of which cannot work loose and become detached.

With the foregoing and other objects in view which will appear as the description 25 proceeds the invention resides in the combination and arrangement of parts and in the details of construction hereinafter described and claimed it being understood that changes in the precise embodiment of the invention 30 herein disclosed may be made within the scope of what is claimed without departing from the spirit of the invention.

In the accompanying drawing the preferred form of the invention has been shown.

35 In said drawing,

Figure 1 is a side elevation of a glide constructed in accordance with the present invention.

40 Figure 2 is a section through the base portion thereof, the stem of the glide being shown, by broken lines, in one of the positions to which it may be shifted relative to the base.

45 Figure 3 is a plan view of the top disk of the connecting structure.

Figure 4 is a side elevation thereof.

Figure 5 is a top plan view of the bottom disk of the connecting structure.

50 Figure 6 is a side elevation thereof.

Figure 7 is a top plan view of a modified

form of disk of the connecting member.

Figure 8 is a view thereof partly in side elevation and partly in section.

Referring to the figures by characters of reference 1 designates a concavo-convex top disk having a central opening 2. Extending around this disk is a depending flange 3 having a flared portion 4 which, in the structures shown in Figures 2, 3, and 4, is formed with depressions 5. The disk 1 constitutes 55 a cap adapted to fit snugly upon a concavo-convex bottom disk 6 curved oppositely to the disk 1 and having a marginal tapered flange 7 formed with an annular depending portion 8 the lower portion of which is flared 60 as shown at 9. These parts are so shaped as to fit snugly against the bottom surface of the concaved portion of disk 1 close to the flange 3 thereof, against the inner surface 65 of said flange, and against the bottom surface of the flared portion 4. The flared portion 9 terminates inwardly from the de- 70 pressions or projections 5.

The base 10 of the glide is formed of a 75 suitable material adapted to be molded to proper shape. This material is adapted to be pressed around and to embed the flared portions 4 and 9 as well as the depending flanges 3 and 8, the projecting portions 5 serving to hold the disk 1 against rotation 80 within the molded base. The bottom surface of the base can be shaped with a rounded or beveled face as indicated at 11 thereby to facilitate gliding over an obstruction.

The molded material will of course fill all 85 spaces below the disk 6 and will act to hold the two disks together securely so that they cannot be separated from each other or from the base.

Before the disks 1 and 6 are joined to 90 the base 10 as explained, the stem 12 of the glide is assembled therewith. This stem is similar to the one commonly employed with furniture casters but its lower end is formed with a rounded foot 13 the diameter of which is greater than the diameter of the opening 2. The opposed concaved portions of the disks 1 and 6 cooperate to retain this foot therebetween but the opening 2 is of such size as 95 to permit the stem 12 to oscillate in any direc- 100

tion, the bottom surface of the foot at all times pressing downwardly against the disk 6 which thus serves to receive wear and to protect the base 10.

- 5 By having the two disks interfit as shown, the material of which the base 10 is formed will not press between the disks while being molded therearound. Instead the space between the concaved surfaces of the disks will 10 be kept clear so that no obstructions will be formed therein which might interfere with the sliding movement of the foot 13 between the disks.

15 As the lower disk 6 receives the thrust from the stem 12 and its foot 13, the strain will be distributed over an extensive part of the base so that the danger of breaking or cracking said base is practically eliminated.

- 20 The primary advantage in having a glide such as described is that, when it is substituted for an ordinary furniture caster, the base 10 will remain flat on the supporting surface even though the article of furniture 25 may be tilted. The base will also adapt itself to an inclined supporting surface. Consequently the danger of breaking the base because of an unequal application of pressure therethrough to the supporting surface or because of the positioning of the base with 30 its contact point remote from the center is entirely avoided. Furthermore the movable connection between the base and the stem permits the base to rock while passing over 35 an obstruction in the path thereof.

Instead of forming the upper disk with depressions 5 as illustrated, the same may be provided with downstruck ears 14 at the margin thereof which will project into the 40 molded base and hold the disk against rotation. This has been clearly illustrated in Figures 7 and 8.

- 45 Two very important features of the present invention are, first, the molding of the glide around the disks so that when the material of the base hardens, the disks will be firmly assembled therewith; and second, the provision of disks which tightly interfit so that 50 when the material of the base is molded under pressure no part thereof will exude into the cavity between the disks.

What is claimed is:

1. A glide including interfitting concavo-convex disks oppositely disposed to provide a 55 space therebetween, there being an aperture in one of the disks, a one-piece base in which the marginal portions of the disks are embedded, said base constituting means for holding the disks against separation a stem 60 having one end movably mounted between the disks, said stem being mounted to swing in any direction within the opening, and means on the stem and cooperating with one of the disks for holding the stem against separation from the base and disk.

2. A glide for furniture and the like including interfitting superposed disks providing a space therebetween, the disks being in contact adjacent their margins a base in which the marginal portions of the disks are 70 embedded, said base constituting means for holding the marginal portions of the disks in contact and against separation from the base, said base also providing a backing for all portions of the lower or inner disk, there being 75 an opening in the other disk, a stem having one end seated between the disks, said stem mounted to swing in any direction within the opening, means on the lower end of the stem cooperating with the disks to hold the stem against withdrawal from engagement with the disks, the lower disk constituting means for transmitting thrust from the stem to an extensive area of the base.

3. A glide for furniture and the like including interfitting superposed disks contacting adjacent their margins but providing a space between the central portions of the disks, a base in which the marginal portions of the disks are embedded, said base constituting means for holding the marginal portions of the disks in contact and against separation from the base, said base also providing a backing for all portions of the lower or inner disk, there being an opening 80 in the other disk, a stem having one end seated between the disks, said stem mounted to swing in any direction within the opening, means on the lower end of the stem cooperating with the disks to hold the stem against withdrawal from engagement with the disks, the lower disk constituting means for transmitting thrust from the stem to an extensive area of the base.

4. A glide for furniture and the like including interfitting members contacting at their margins and providing a cavity between the middle portions of the members, and a 110 base in which the marginal portions of the members are embedded, said base constituting means for holding said members in contact and against separation from the base.

In testimony that I claim the foregoing as 115 my own, I have hereto affixed my signature.

GEORGE J. OVERMYER.
